UNITED STATES PATENT OFFICE.

VINCENT STRUOGIS, OF NEW YORK, N. Y.

DESIGN FOR A FLAG OR SIMILAR ARTICLE.

45,731.

Specification for Design.

Patented May 5, 1914.

Application filed March 2, 1914. Serial No. 822,064. Term of patent 14 years.

To all whom it may concern:

Be it known that I, VINCENT STRUOGIS, a citizen of the United States, residing in the borough of Brooklyn, county of Kings, city and State of New York, have invented a new, original, and ornamental design for a Flag or Similar Article, of which the following is a specification, reference being had to the accompanying drawing, forming a part thereof.

The figure is a front view of a flag or similar article showing my new design.

I claim:

The ornamental design for a flag or similar article as shown.

This specification signed and witnessed this 27th day of February, 1914.

VINCENT STRUOGIS.
